UNITED STATES PATENT OFFICE.

ALWIN VON AUW, OF BROOKLYN, NEW YORK, ASSIGNOR TO BOORUM & PEASE COMPANY, OF BROOKLYN, NEW YORK, A CORPORATION OF NEW YORK.

VISIBLE CARD INDEX.

Application filed July 13, 1926. Serial No. 122,180.

This invention relates to the overlapping type of visible index in which the cards have hinged slidable mounting and more particularly to the novel form of mounting the cards on the panel or support. In the index to which my invention relates a single downwardly depending ear is formed entirely outside the body of the card on each side thereof, and adapted to lie partly under the flange of the panel.

The association between one card and its neighbor is such that while there is engagement between the cards even when they are not in the panel, yet that association avoids the disadvantages of nested cards and permits the ready removal or insertion of any card in the series while the cards are in the panel, without sliding the other cards apart. Another object of my invention is to provide a form of card which is at the same time economical to manufacture and extremely simple in manipulation. Another object of my invention is to provide a form of index card which has all the advantages of direct interconnection between the cards and also all the advantages of the non-nesting type of card. Another object of my invention is to provide a perfectly flat surface for the body of the card with corresponding advantages in ease of writing thereon. A further advantage of my construction is that by merely tearing or cutting off the depending ears, one obtains a card exactly like the ordinary vertical index card, which can of course be filed away in a vertical index if desired. Another object of my invention is to provide a form of visible index in which the whole of both sides of each card is available while the card is in the panel.

In the drawings:

Fig. 1 is a plan view of my new index card;

Fig. 2 is a plan view of a portion of my panel containing a series of cards, the flanges being partly broken away;

Fig. 3 is an exaggerated vertical section through the ears of the cards on the line 3—3 of Fig. 2;

Fig. 4 is a plan view of a portion of the panel showing the first step of inserting a new card between two cards already in the panel;

Fig. 5 is a plan view of one edge of a portion of the panel showing a later stage of in-

serting a new card between two cards already 55 in the panel;

Fig. 6 is similar to Figs. 4 and 5 and shows the insertion of the second ear of the card in the panel; while

Fig. 7 is a view similar to Figs. 4, 5, and 60 6, showing the addition of a card at the top of the series.

This invention relates to the type of visible index in which the cards are slidably mounted on a panel in such manner as to be hinged 65 with relation thereto and yet at the same time be individually removable therefrom. To obtain this complete flexibility in arrangement and ready insertion and removal, and yet at the same time have an index of the 70 utmost simplicity and compactness, I use a panel 10 having flanges 11 forming opposed inwardly facing grooves spaced a distance apart which is greater than the width of the body of the cards by perhaps $\frac{1}{8}$ or $\frac{1}{4}$ of an 75 inch. Thus when making an index for the standard 3 x 5 cards, the inner edges of the opposed flanges will be perhaps $5\frac{1}{8}$ or $5\frac{1}{4}$ inches apart.

The cards, which together with the panel 80 form my index, each consists of a body portion 10 with a depending ear 14 on each side of the card outside the body portion. These ears may, if desired, be formed integrally with the card out of one piece of sheet material, thus eliminating the necessity for individual metal carriers. In the drawings the body portion has been shown as consisting of a rectangular portion which may correspond to the ordinary record card, hinged to a 85 narrow strip which, with the ears, would constitute a carrier. These depending ears preferably lie close to the sides of the body of the card and extend outwardly to a width which insures adequate overlap with the 90 flanges with which they cooperate. I prefer to make the ears wide enough to use their outer edges as guides against sideways movement. Each ear consists essentially of an oblong portion outside of and severed from 100 the body of the card from the lower end up to a point 16 perhaps $\frac{1}{4}$ of an inch from the top of the card. In making this severance it is preferable not to cut away any material. These depending ears can be as long 105 as desired, although I prefer to make them about an inch, or even less, measuring from the top of the card. These very simple ex-

ternal ears when combined with the panel having flanges spaced as above described form a peculiarly useful combination for index purposes, and especially so when the 5 cards are hinged by making a weakened line 15 in the card reaching from one free side edge of the body portion 10 to the other, i. e. either opposite or below the juncture between the ears and the remainder of the 10 card. This weakened line should preferably be on a line joining the upper ends of the incisions between the depending tongues and the body of the card. The ears and the portion of the card above the hinge line may be 15 considered a carrier for the rectangular portion of the card and may be made separately if desired. In the drawings the depending portion or point of the ear is numbered 17 and the part above the juncture with the 20 body is numbered 18. The upper edge of the card is numbered 19 and the body 12.

Assuming that the cards are to be assembled as a unit before being put in the panel, the cards are associated in a manner which 25 will now be described. One card is added above the other by simply placing the new card on top of the previous card with the depending portions 17 of the ears of the upper card behind the depending ears of the card below but with the body 12 of the upper card in front of the body of the card below. The whole series of cards are then mounted on the panel by inserting the ears under the flanges. 30 This can be done by sliding the cards in from one end of the panel, or at any desired intermediate point by flexing the cards along a vertical median line in the well known manner and inserting one column of ears at a time.

40 Similarly when adding a card at the lower end of a series in the panel 10, the upper edge 19 of the new card is associated with the card above by placing it behind the body 12 of the last card in the series but in front 45 of the depending ears of that card.

Assuming that it is desired to add a card to the top of a series already in the panel, the new card is grasped at the upper edge near its middle and brought down to the 50 cards in the panel from above at a slight angle, as indicated in the drawings. The depending ear of the new card is slid a slight distance under the upper edge of the top card and is then slid sideways underneath the flange, (Fig. 7). This end of the card 55 may now be pushed downwardly till the juncture point 16 between the depending ear and the body of the card engages against the upper edge of the top card of the series already in the panel. The other end of the new card is then brought down nearer to the top of the card already in the panel, the new card being flexed at the middle as 60 already mentioned, and the depending ear 65 on this second end of the new card is pushed

a slight distance under the upper edge of the card already in the panel, but not a sufficient distance to carry it below the joined portion 18 of the ear of the card below. The operation is completed by allowing the 70 ear of the new card to slide sideways under the flange and pushing that end of the card down as before.

If a card is to be inserted at the bottom of a series already in the panel, the upper corners of the new card are each in turn placed on top of the exposed portions of the depending ears of the bottom card of the series and then slid in between the exposed 75 edge and the lower tongue of the flange, the 80 body of the bottom card of the series already having been turned up.

If a card is to be added in the middle of a series of cards already in the panel, the cards are separated until there is a space 85 equal to the amount of overlap between one card and its neighbor, i. e., the depth of the union between the ears and the body portion. The card is then grasped as when placing the card at the top of the series, each 90 ear being placed in position successively as shown in Figs. 4, 5 and 6. The lower end of the first ear to be positioned is placed under the upper edge 19 of the card below and slid outwardly until the edge of the 95 tongue of the new card is on top of the edge of the tongue above. The edge of the tongue of the new card is then laid down on top of the tongue of the card above and slid under the flange. The manner of insertion 100 at the other end will be obvious from the descriptions already given.

It will be observed that while the cards are associated together in such a manner that they can be carried as a unit without a 105 panel, the disadvantages of nested cards are avoided. Thus when the cards are in the panel, a card can be removed from any part of the series without disturbing the cards above or below the one to be removed. To remove a card from the series it is merely necessary to fold back the cards above without sliding them lengthwise of the panel at all and the card can be removed by simply 110 sliding it upward over the folded back rectangular portions of the cards above and either twisting the card sideways or flexing it along the median line, as already mentioned. It will be observed that the maintenance of the overlap of the cards depends 115 upon the cards lying flat rather than turned back along the hinge line and this straddle of the upper edge of the card below by two elements which are laterally adjacent but not overlapping and hinged to each other as 120 described, is one of the points of novelty of the invention.

What I claim is:

1. A visible index card made of one integral piece of sheet material comprising a 125

- body portion in combination with a depending ear on either side of said body portion at the upper edge, said ears lying close to the body portion below the juncture between 5 said body portion and said ears.
2. A visible index card comprising a body portion in combination with a depending ear at either side of said body portion at the upper edge, said body portion being hinged 10 on a line reaching from one free side edge of said body portion to the other.
3. An integral visible index card comprising a body portion in combination with suspending and spacing means outside said 15 body portion comprising a downwardly hanging ear joined thereto on each side at the upper edge thereof, said body portion being hinged on a line joining the points of severance between the body portion and 20 the ears.
4. A visible index comprising a panel having inwardly facing opposed grooves in combination with a series of cards mounted 25 therein, each card comprising a body portion overlying the body portion of the card below and means attached to either side of the body portion underlying the corresponding means of the card below.
5. A visible index comprising a panel 30 having inwardly facing opposed flanges in combination with a series of overlapping hinged cards each comprising a body portion overlying the body portion of the card below and a depending ear attached to each 35 side of the body portion at its upper edge underlying the corresponding flange and the ear of the card below, and extending inwardly beyond that flange.
6. A visible index comprising a panel
- having inwardly facing opposed grooves in combination with a series of cards slidably mounted in said grooves, each card comprising a body portion overlying the body portion of the card below but narrower than the distance between the grooves of the panel, and a downwardly hanging ear joined to each side of the body portion at its upper edge underlying an ear of the card below and extending inwardly of the corresponding groove.
7. A visible index comprising a panel having inwardly facing opposed flanges in combination with a series of overlapping hinged cards each comprising a body portion overlying the body portion of the card 55 below and a depending ear integral with the body portion at each side thereof at its upper edge underlying the corresponding ear of the card below and the flange but extending inwardly of the latter, there being a 60 hinge line joining the points of severance between the ears and the card.
8. A visible index comprising a panel having inwardly facing opposed flanges in combination with a series of overlapping hinged 65 cards each comprising a rectangular portion and a carrier hinged to the upper edge of the rectangular portion, said carrier having depending ears extending outwardly to the full width of the grooves formed by the 70 flanges and extending inwardly beyond said flanges, said ears underlying the corresponding ears of the card below, substantially as described.

In testimony whereof I have signed my 75 name to this specification.

ALWIN VON AUW.
